UNITED STATES PATENT OFFICE.

ALONZO E. RHOADES, OF HOPEDALE, MASSACHUSETTS, ASSIGNOR TO THE HOPEDALE MACHINE COMPANY, OF SAME PLACE.

RISE-ROLL MECHANISM FOR WARPING-MACHINES.

SPECIFICATION forming part of Letters Patent No. 500,541, dated June 27, 1893.

Application filed February 18, 1893. Serial No. 462,827. (No model.)

To all whom it may concern:

Be it known that I, ALONZO E. RHOADES, of Hopedale, county of Worcester, State of Massachusetts, have invented an Improvement in Rise-Roll Mechanism for Warping-Machines, of which the following description, in connection with the accompanying drawings, is a specification, like letters and figures on the drawings representing like parts.

- 10 It is customary in warping machines to mount the "rise-roll" for taking care of the slack in the warps, on independent vertically movable bars or bearings sustained by suitable weights, but such construction is objectionable because of the liability of the roll descending unequally at its ends. To obviate this trouble, I have devised means whereby the rise-roll is compelled to move for exactly the same distance at each end, and this I have 15 accomplished by providing the bearing bars with rack teeth which are engaged by pinions on a cross shaft, said shaft having a suitable drum from which is suspended a weight.

Figure 1, is a partial end view of a sufficient portion of a warping machine with my improvements added to enable my invention to be understood. Fig. 2, is a left-hand side view thereof, partially broken out, however, at one end to better show the construction of the 20 parts; and Fig. 3, a detail to be referred to.

The frame-work A, the reed a, and the guide-rolls b, c, d, are and may be of any usual or suitable construction.

The rise-roll e has its journals in suitable 35 bearings at the upper end of bearing bars e', e' fitted in suitable vertical guide-ways formed at the inner sides of the frame-work, said bars being suitably toothed, as at 2, as best shown in Fig. 2, said teeth being engaged by the pinions f, f' on a shaft f² extended across the 40 machine and having its journals supported in suitable stands f³ of the frame-work, said shaft serving to connect said bearing bars in such manner that they must rise and fall in unison, and consequently the ends of the rise-roll must rise and fall in unison, and the rise-roll once set truly horizontal will always remain so. This rise-roll is made to bear 45 constantly and uniformly against the warp w from one to the other selvage warp by a force

measured by the weight g which may be made more or less according to the material being acted upon, said weight being shown as connected by a flexible connection h, a cord or chain, adapted to be wound on a drum m, 55 preferably of conical form and grooved to resemble a fusee. The shape of the bearing bars in cross section is best shown in Fig. 3, and as shown in said figure, in the top of each bar is a depression, as at e², to receive the 60 journal of the rise-roll e. The bearing bars are provided at their back and front edges with V-shaped grooves 3 see Fig. 3 which are entered by V-shaped projections 4 of the upright guide-ways n, shown as bolted to the 65 frame-work by bolts n'.

Having described my invention, what I claim as new, and desire to secure by Letters Patent, is—

1. In a warping machine, guide rolls over 70 which the warp threads run from a set of spools to a beam, and a rise-roll or bar over which said threads run, said rise-roll or bar being arranged to vary its level as the tension on the warp threads changes, combined with 75 guides to receive and support the ends of the said rise-roll or bar, and devices including rack teeth and pinions to normally lift the rise-roll or bar at its opposite ends for equal 80 distances and always maintain said roll or bar in horizontal position throughout its movements, substantially as described.

2. In mechanism for controlling warps, 85 guide-rolls, and a rise-roll and toothed bearing-bars for the journals of said rise-roll, combined with a cross-shaft having gears to engage the teeth of and connect the said bearing-bars, and a weight co-operating with said shaft to normally keep the rise-roll pressed toward the warp, the combination being and 90 operating substantially as described, whereby by uniformity of movement and action of the rise-roll is insured, as set forth.

In testimony whereof I have signed my name to this specification in the presence of 95 two subscribing witnesses.

ALONZO E. RHOADES.
